DESIGN FOR A CHILD'S SLIPPER OR SIMILAR ARTICLE

Henri E. Rosen, Brookline, Mass.

Application July 9, 1945, Serial No. 120,578

Term of patent 14 years

(Cl. D7—7)

To all whom it may concern:

Be it known that I, Henri E. Rosen, a citizen of the United States of America, residing at Brookline, in the county of Norfolk and Commonwealth of Massachusetts, have invented a new, original, and ornamental Design for a Child's Slipper or Similar Article, of which the following is a specification, reference being had to the accompanying drawing, forming a part thereof, and wherein

Fig. 1 is a side elevational view of a slipper showing my new design;

Fig. 2 is a plan view;

Fig. 3 is a front elevational view; and

Fig. 4 is a bottom view of the slipper shown in Fig. 1.

I claim:

The ornamental design for a child's slipper or similar article, substantially as shown.

HENRI E. ROSEN.
